(57) **CLAIM**

The ornamental design for a battery pack, as shown and described.

DESCRIPTION

FIG. 1 is a top left side perspective view of the battery pack.
FIG. 2 is a top view of the battery pack.

FIG. 3 is a front view of the battery pack, the rear view being a mirror image thereof.

FIG. 4 is a bottom perspective view of the battery pack, showing it plugged into a mouse; and,

FIG. 5 is a top front perspective view of the battery pack, showing a charging base station underneath the battery pack. The broken lines in the drawings are for the purpose of illustrating environmental structure and form no part of the claimed design.
